CIRCULATING AIR HEATING FURNACE
WITH INTERNAL AIR HEATING CONDUIT

Earl F. Fromme, Kirksville, Mo.

Application August 1, 1950, Serial No. 177,099

3 Claims. (Cl. 126—110)

1

This invention relates to an improved circulating air heater, especially, but not exclusively, of the oil or gas-fired type, and the primary object of the invention is to provide a more efficient and practical heater of this kind which utilizes a greater proportion of the heat generated by the heating element, and which enables better control and distribution of the hot air discharged by the heater into a room or other space to be heated, whereby increased heating efficiency is obtained compared to other air heaters of similar capacity.

Another important object of the invention is to provide an air heater of the character indicated above in which the intake of cool air and the circulation within the heater of both the intaken cool air and the hot air heated therein and the output of the hot air from the heater are produced by a single blower.

A further important object of the invention is to provide a compact and relatively inexpensive air heater of the character indicated above in which the intaken cool air is circulated initially in contact with the outside of a barrel heated by and surrounding a conduit serving as a flame spreader, against which flame from the heating element plays, whence a portion of the thus initially heated air passes through the flame spreader conduit to be highly heated therein, the resultant highly heated air then passing from the flame spreader conduit along and in contact with the outside of the barrel toward the output of the heater, a portion of the initially heated air not passing through the flame spreader conduit being arranged to be introduced into the stream of the highly heated air as the latter passes in contact with the outside of the barrel on its way to the heater output.

A still further important object of the invention is to provide an air heater of the character indicated above wherein the cool air intake means and the heated air output means are in a base at floor level, whereby circulation of heated air within a room from floor to ceiling can be obtained to provide a uniform temperature from floor to ceiling.

Other important objects and advantageous features of the invention will be apparent from the following description and the accompanying drawings, wherein, for purposes of illustration only, a specific embodiment of the invention set forth in detail.

In the drawings, wherein like numerals designate like parts throughout the several views:

Figure 1 is a transverse vertical section taken on the line 1—1 of Figure 2;

Figure 2 is a top plan view with the outer casing removed, certain internal structure being shown in dotted lines;

Figure 3 is a fragmentary, left-hand side elevation of Figure 2, partly broken away, to show internal structure;

Figures 4 and 5 are horizontal sections taken

2

on the lines 4—4 and 5—5, respectively, of Figure 1, the casing being removed.

Referring in detail to the drawings, the illustrated air heater comprises a hollow substantially square, relatively flat or shallow base 7 having a bottom wall 8, a top wall 9 and side walls 10 connecting the outer edges of the bottom and top walls. Within the base 7 at one side thereof, in the case of use of an oil burner as the heating element, is a generally triangular oil sump 11 having a drain pipe 12 at one corner thereof depending through the bottom wall 8. Positioned within the oil sump 11 is a conventional form of carburetor 13 having suitable connection (not shown) to an oil burner 14. The oil burner 14 is mounted on and rises above the base top wall 9 somewhat forwardly of center position, as indicated in dotted lines in Figure 2.

The interior of the base 7 is divided into a rear cool air chamber or space 15 and a forward heated air chamber or space 16 by a partition or wall 17 extending across the interior of the base between the sides thereof. As indicated in Figures 2 and 3, the wall 17 may have one end thereof connected to the wall 11' of the sump 11, in which case the sump acts as a part of the partition 17. As shown in Fig. 2, the rear side wall of the base 7 has a cool air inlet 18 near the right-hand end thereof, and the left-hand side wall has another cool air inlet 19 near the rear end thereof, both inlets communicating exclusively with the cool air chamber 15. The front base side wall has left and right-hand heated air outlets 20 and 21, respectively, near the left and right-hand ends thereof; and a third heated air outlet 22 on the forward end part of the left-hand base side wall, all of the outlets 20, 21 and 22 communicating exclusively with the heated air chamber 16. The various inlets and outlets are in the form of screened ports with which suitable air flow-controlling means (not shown) can be readily associated to afford accurate control of air circulation. A removable casing 23, of vertically elongated, rectangular form, is adapted to rest its lower end on the base 7 and enclose the upper surface of the top wall 9 thereof, and be secured in position by suitable means (not shown). The casing 23 has a top wall 24 provided with a flue opening 25, and side walls 26 provided at vertical intervals with perforations or gratings 27 providing for a certain amount of direct convection heating of room air outside of the heater casing.

Rising from the base top wall 9 around the burner or fire pot 14 is the tubular, cylindrical inner or heating barrel 28, which is closed at its lower end, as indicated at 29, and has a closed horizontal upper end. An eccentric flue pipe 31 rises from the upper end 30 and extends through the flue opening 25 in the casing top wall 24 approximately centrally of the casing 23.

The upper end 30 of the barrel 28 is spaced downwardly from the casing top wall 24, as shown in Figure 1. The lower end 29 of the barrel 28 is provided with a depending updraft pipe 32 through which combustion air from a suitable source (not shown) rises through the barrel 28, feeds the burner 14, and carries the flame and products of combustion upwardly in the barrel and out through the flue pipe 31 to a place outside of the room in which the heater 7 is located.

Supported in concentrically spaced relation within the upper part of the barrel 28 and in spaced relation above its burner 14 is the air-heating conduit 33 which includes an inverted hollow frusto-conical burner flame-spreader 34 and a helical, tubular heating coil 35 above the flame-spreader. The lower end of the coil 35 has a laterally offset, depending portion 36 connected to one side of the top of the spreader 34 and communicating with the interior of the spreader. The opposite side of the top of the spreader 34 has a lateral tubular part 37 extending to and opening through the side wall 33 of the barrel 28, as a port 39 located intermediate the upper and lower ends of the barrel 28. The upper end of the coil 35 has a laterally directed portion 40 reaching to and opening through the barrel side wall 33 as a port 41, located close to its upper end 38. A baffle plate 42 formed with perforations 43 is positioned between the uppermost and the next lower convolutions of the coil 35, to retard the upward passage of hot products of combustion through the coil 35 and thereby obtain a greater heat transfer to the coil 35.

Concentrically spaced around the barrel 28, as indicated in Figures 2, 4 and 5, is the tubular, cylindrical outer barrel 45 which rises from the top wall 9 of the base 7. The left-hand side of the side wall 46 of the outer barrel 45 as seen in the drawings is provided with a radial offset 47 of rectangular, horizontal cross-section which has plane front and rear side walls 48 and 48', respectively, joined to the outer barrel side wall 46, and a plane outer wall 49 joining the outer ends of the side walls 48 and 48', as shown in Figures 2, 4 and 5. The offset 47 extends from the lower end of the outer barrel 45, which is closed by the base top wall 9, to the upper end of the barrel 45. The upper end of the offset 47 is closed by a plate 50, which also closes the upper end of the outer barrel 45 and is provided with an opening through which the flue pipe 31 passes.

A vertical baffle plate 51, extending the full height of the outer barrel 45 has its radially outward edge secured to the outer wall 49 of the offset 47 and is parallel to and equally spaced from the offset side walls 48 and 48'. The baffle plate 51 reaches to the outer cylinder 45 and has its radially inward edge secured to the adjacent part of the side wall 33 of the inner barrel 28. The upper end of the baffle plate 51 has an extension 52 which reaches across the upper end 30 of the inner barrel 28, and extends vertically between the upper end 30 and the top 53 of the outer barrel 45. The extension 52 reaches only about one-third of the distance across the top 30 of the inner barrel 28. The lower end of the hot air duct 56 of the offset 47 defined by the rear side wall 48, the outer wall 49, and the baffle plate 51, is open, as indicated at 55, to the interior of the hot air chamber 16 within the base 7, but the lower end of the companion cool

air duct 54 in the offset 47 on the opposite side of the baffle plate 51 is closed by the top wall 9 of the base 7.

As a result of the foregoing structure, the space between the inner and outer barrels 28 and 45, respectively, is in open and direct communication with the cool air duct 54 and the hot air duct 56.

A preferably push-pull type of electric blower 60 has its housing 61 mounted on the top wall 9 of the base 7 to the rear and to the right of the outer barrel 45 and has its tangential output pipe 62 extended forwardly to the rear side wall 48', of the offset 47, through which the pipe 62 opens. The intake side of the blower 60 is in communication with the cool air chamber 15 of the base 7 through an opening 63 provided in the base top wall 9. A clean-out housing 59 extends through and beyond the front side wall 46 of the outer barrel 45 and is secured to the inner barrel 28 for easy access to the interior of the inner barrel 28 and is sealed against escape of air when closed. A strip 59' surrounding the housing 59 extends between and is secured to both the inner barrel 28 and the outer barrel 45 for reinforcement thereof.

In operation, the burner 14 and the blower 60 being in operation, cool room air is drawn from a level near the floor into the cool air chamber 15 of the base 7 through the inlets 18 and 19 and forced upwardly in the cool air duct 54 of the offset 47 and around the adjacent side of the inner barrel 28. As the cool air rises in contact with the outside of the inner barrel 28, the air is initially heated thereby. As the initially heated air rises in the duct 54 toward the top 50 of the outer barrel 45, part thereof passes through the port 41 and flows downwardly through coil 35 and flame-spreader 34, thereby being heated to the highest degree. The port 39 with which the flame-spreader 34 connects being in communication only with the hot air duct 54, the highly heated air passing downwardly through the coil 35 and spreader 34 passes downwardly therein and through the base top opening 55 into the hot or heated air chamber in the forward part of the base 7, from which the hot air escapes through the outlets 20, 21 and 22 into the room at floor level. In the rise of the initially heated air toward the upper ends of the inner barrel 28 and outer barrel 45, such of this air as does not pass through the port 41 into the heating conduit 33 passes around the inner barrel 28 and over the top of the inner barrel along the adjacent side of the baffle plate extension 52 and flue pipe 31 and upon reaching the opposite side of the inner barrel 28, joins the downward circulation of heated air in the hot air conduit 56, the circulation of heated air around the inner barrel being in a counterclockwise direction.

It will be seen from the foregoing that there is a continuous flow of air through the heater while the blower 60 is in operation, and that with the burner 14 also in operation, there are several stages of desirable heat exchange, both conductive and convective, between hot portions of the heater and the circulating air and between heated portions of the circulating air and cooler portions of the circulating air, whereby the air outputted from the heater is at a higher temperature and in greater volume than is the case with other heaters of similar capacity.

I claim:

1. In an air-circulating heater, a closed hollow base, partition means dividing the interior of

said base into a cool air chamber and a heated air chamber, air inlet means for said cool air chamber, outlet means for said heated air chamber, an inner tubular heating barrel mounted upon said base and having its lower end closed by a portion on said base, a burner within the lower end of said heating barrel, a restricted combustion air inlet leading into the lower end of said inner barrel, said inner barrel having a closed upper end, a restricted flue pipe leading from the upper end of said inner barrel, an outer barrel having a lower end mounted upon and closed by said base, said outer barrel spacedly surrounding said inner barrel and having a closed upper end spaced above the upper end of said inner barrel, the space between said inner and outer barrels forming an air heating space, a baffle extending from said base to the closed upper end of the outer barrel and reaching across the space between the inner and outer barrels on one side thereof only whereby the air heating space provides a U-shaped passageway extending around the inner barrel, an air heating conduit within said inner barrel and located above and in heat exchange relation to said burner, said conduit having an end leading from the inner barrel into said space at one side of said baffle and having another end opening into said space at the opposite side of said baffle, means providing communication between said heated air chamber and said air heating space at one side of and adjacent said baffle, a blower having an intake communicating with said cool air chamber and an outlet communicating with said air heating space at the other side of and adjacent the baffle whereby cool air is indrawn into said cool air chamber through said inlet means and is discharged into said space to circulate around the inner and outer barrels and move from said hot air space into the hot air chamber of the base and discharge therefrom through said outlet means.

2. In an air-circulating heater, a closed hollow base, partition means dividing the interior of said base into a cool air chamber and a heated air chamber, air inlet means for said cool air chamber, outlet means for said heated air chamber, an inner tubular heating barrel mounted upon said base and having its lower end closed by a portion on said base, a burner within the lower end of said heating barrel, a restricted combustion air inlet leading into the lower end of said inner barrel, said inner barrel having a closed upper end, a restricted flue pipe leading from the upper end of said inner barrel, an outer barrel having a lower end mounted upon and closed by said base, said outer barrel spacedly surrounding said inner barrel and having a closed upper end spaced above the upper end of said inner barrel, the space between said inner and outer barrels forming an air heating space, a baffle extending from said base to the closed upper end of the outer barrel and reaching across the space between the inner and outer barrels on one side thereof only whereby the air heating space provides a U-shaped passageway extending around the inner barrel, an air heating conduit within said inner barrel and located above and in heat exchange relation to said burner, said conduit having an end leading from the inner barrel into said space at one side of said baffle and having another end opening into said space at the opposite side of said baffle, means providing communication between said heated air chamber and said air heating space

5 at one side of and adjacent said baffle, a blower having an intake communicating with said cool air chamber and an outlet communicating with said air heating space at the other side of and adjacent the baffle whereby cool air is indrawn into said cool air chamber through said inlet means and is discharged into said space to circulate around the inner and outer barrels and move from said hot air space into the hot air chamber of the base and discharge therefrom through said outlet means, the said ends of said air heating conduit being in substantially vertically spaced relation to each other.

3. In an air-circulating heater, a closed hollow base, partition means dividing the interior of said base into a cool air chamber and a heated air chamber, air inlet means for said cool air chamber, outlet means for said heated air chamber, an inner tubular heating barrel mounted upon said base and having its lower end closed by a portion on said base, a burner within the lower end of said heating barrel, a restricted combustion air inlet leading into the lower end of said inner barrel, said inner barrel having a closed upper end, a restricted flue pipe leading from the upper end of said inner barrel, an outer barrel having a lower end mounted upon and closed by said base, said outer barrel spacedly surrounding said inner barrel and having a closed upper end spaced above the upper end of said inner barrel, the space between said inner and outer barrels forming an air heating space, a baffle extending from said base to the closed upper end of the outer barrel and reaching vertically across the space between the inner and outer barrels on one side thereof only whereby the air heating space provides a U-shaped passageway extending around the inner barrel, an air heating conduit within said inner barrel and located above and in heat exchange relation to said burner, said conduit having an end leading from the inner barrel into said space at one side of said baffle and having another end opening into said space at the opposite side of said baffle, means providing communication between said heated air chamber and said air heating space at one side of and adjacent said baffle, a blower having an intake communicating with said cool air chamber and an outlet communicating with said air heating space at the other side of and adjacent the baffle whereby cool air is indrawn into said cool air chamber through said inlet means and is discharged into said space to circulate around the inner and outer barrels and move from said hot air space into the hot air chamber of the base and discharge therefrom through said outlet means, said baffle including a portion on the upper end thereof extending across the space between the upper end of the inner barrel and the upper end of the outer barrel.

EARL F. FROMME.
